[57] CLAIM

The ornamental design for a personal computer monitor, as shown and described.

DESCRIPTION

FIG. 1 is a right, front, and top perspective view of the personal computer monitor, showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a rear elevational view thereof; and,

FIG. 7 is a bottom plan view.

The pattern partially shown in FIGS. 1-5 and 7 is understood to represent a conventional speaker cover wherein it is understood to continue uniformly across each of the indicated surfaces.
